UNITED STATES PATENT OFFICE

CARL W. BRENN, OF MONTCLAIR, NEW JERSEY

FOLDING MACHINE

Application filed November 14, 1928. Serial No. 319,315.

This invention relates to folding fabric strips, and more particularly to means for folding in zig-zag fashion paper strips for use in manifolding machines.

Such paper strips usually consist of a succession of printed forms or tickets between each two of which is provided a line of perforations. The strips are folded in zig-zag fashion for use in manifolding machines and it is imperative that the folds occur directly on the lines of perforations, for, should the folds be located either ahead or behind the lines of perforations, difficulty is frequently encountered in the manifolding machine incidental to the operation of severing one form or ticket from the next. Moreover, when the folds do not lie directly on the lines of perforations, the pile of zig-zag forms is liable to "pitch", that is it may lean in one direction or the other, and hence assume over-all dimensions too great to properly fit in the machine.

Although several attempts have been made heretofore to fold such continuous manifolding strips in zig-zag fashion by machine, these have not been successful due to the difficulty in causing the folds to occur directly on the lines of perforations between forms. Hence, it has been and still is the custom to fold the strips by hand.

It is an important object of this invention to provide a folding machine which will accurately and properly fold printed and perforated paper strips so that the folds will be located invariably directly upon the lines of perforations. This is accomplished by the present invention by accurately and positively controlling the position of the paper strip at the time of folding by suitable means, and then engaging the paper strip by means which will cause the strip to break-down at its weakest points, namely along the lines of perforations, and become creased.

To do this, the present invention provides accurate feed mechanism (or, when the folder is used in direct conjunction with a printing press, the feeding mechanism of the press) and provides for holding the web on the line of perforations by a gaging device

while a creaser engages the web to fold it over the gaging device and sharply crease it where the fold occurs. The mode of operation of the folding device of the present invention is radically different from that of the gripper and tucker type known to the art of folding, for in the latter paper is drawn from both directions, that is to say ahead of and behind the folder when the tucker forces the paper into the gripper to make the fold, and hence the paper cannot be held tight or taut from either side of the tucker. With the gaging creaser of this invention, one side of the fold may be and is firmly held stationary with the line of fold in a predetermined position during the folding operation, and this position being definite may be accurately controlled by the feeding mechanism.

According to this invention as illustrated herein, the gage and gripper are used only to form the folds extending in one direction, yet a duplicate of such means may be used for the folds of the other direction, if desired. However, since the latter folds are easily formed when the former folds are properly made and held, it has been found that simply pressing out the loop formed in the web is sufficient to properly form these other folds.

Therefore, in the machine disclosed herein, the right-hand folds (as viewed) are formed by the gage device and creaser, while the left-hand folds (again as viewed) are formed by a brush adapted to travel over the looped portion of the web and press it down so that the web creases along the line of perforations.

Other ancillary and equally important features and advantages will hereinafter appear.

In the accompanying drawings which show one form of the invention and which are exemplary thereof—

Figure 1 is a side view of the delivery end of a printing press showing the present invention mounted thereon.

Fig. 2 is a sectional side view showing the folding mechanism with the parts in the po-

sitions they occupy just after the right-hand fold has been formed.

Fig. 3 is a view similar to Fig. 2, but showing the parts in the positions they occupy 5 during the continuation of the feed of the paper, the gage bar having been retracted.

Fig. 4 is a view similar to Figs. 2 and 3, and shows the position of the parts when feeding of the web has been completed and 10 before the left-hand fold is formed.

Fig. 5 is like Fig. 4, but shows the brush in operation for forming one left-hand fold.

Fig. 6 shows the left-hand fold as having been formed and creased.

15 Fig. 7 shows the left-hand and right-hand folds as having just been released by the table and spring fingers after the completion of the folds and the folding plate in position to hold the web for the formation 20 of the next right-hand fold.

Fig. 8 is a transverse sectional view of the folding device taken on the line 8—8 of Fig. 7.

25 Fig. 9 is a top plan view of the gage plate and creaser plate showing them in co-operating positions.

Fig. 10 is a transverse sectional view taken on the line 10—10 of Fig. 6.

30 Fig. 11 is a side view of the portion of the frame work showing the driving connection between the main drive shaft of the press and the folding mechanism.

35 Fig. 12 is an edge view of the mechanism shown in Fig. 11, and showing the printing press frame and folder frame in section.

The device of the present invention, as shown in the accompanying drawings, is adapted for use with printing presses having an intermittent feed and is shown as 40 being attached to the end 10 of the frame 11 of a printing press (see Fig. 1) in which the feed rollers 12 are driven by a gear 13 through a ratchet device of usual construction, not shown. The gear 13 is oscillated 45 by a segment 14 pivoted at 15 having an arm 16 connected with a pitman 17 carried by a face plate 18 driven by the power shaft 19 which runs longitudinally of the printing press frame and which is shown in Figs. 11 50 and 12.

55 The press is of the "all size" type, that is to say it prints forms of various lengths, and hence the intermittent operation of the press is arranged to be universally varied between maximum and minimum limits. For this purpose, the pitman 17 has a connection 20 to the face plate 18 which is adjustable radially of the face plate, so that 60 the length of throw of the segment 14 for each revolution of the face plate may be varied, it being understood that the ratchet connection, which is not shown, between the gear 13 and the feed rollers 12, permits 65 retrograde movement of the segment 14 on

the back stroke of the pitman, independently of the feed rollers.

As stated above, it has long been considered impracticable to provide for transversely folding the printed web in conjunction with an "all size" printing press, for the reason that separate grippers and tuckers of the known types of folding devices would have to be provided for each of a number of "standard" size forms. In the business of printing continuous manifolding strips, there are 6 or 7 standardized sizes which would require the provision of 6 or 7 70 separate gripper and tucker arrangements, only one of which, of course, could be used at a time and the rest of which would be idle and hence unproductive, representing a loss in capital investment and space.

75 By the present invention, however, it has been found to be feasible to provide a folding device for an "all size" printing press, and this folding device, instead of operating on the gripper and tucker principle, operates to cause the fold to occur in a predetermined place in the web under the sole control of 80 the feeding means which being, as it is, sufficiently accurate for feeding the forms, is just as sufficiently accurate for determining the folding position of the web. Hence, 85 it is positively assured that the fold will always occur at that predetermined point and this is extremely important, for the fold should occur at the junction of two adjacent forms, particularly when that junction is 90 defined by a line of perforations or other 95 weakening arrangements to facilitate severance of the web into sheets, as when being used in a manifolding machine.

99 It will thus be seen that accurate feeding means, whether considered part of a press or part of the folding machine, forms a part 100 of the present invention, for, as stated, it is by the feeding means that the line of fold is determined.

One of the salient features, which has resulted in accomplishing the objects of the present invention, is the provision of separate means for producing the right and left hand folds in the web, the points of fold being in both cases positively controlled 110 by the feeding means. Another is the provision of means for variably controlling the device to accommodate forms of all sizes. This latter is accomplished by mounting the folding device in a frame 21 which is adjustably mounted on the extension 10 of the printing press frame 11, as will hereinafter appear.

120 As stated, the web is intermittently advanced by the feed rollers 12. After leaving the latter, the web 22, which has been printed and which has been provided with a longitudinal series of transversely disposed lines of perforations 23 by a perforating device 24 (see Fig. 1), passes over a 125 130

paper table 25 fixed in the folding device frame 21; and from the paper table 25 the web 22 reaches to a ledger bar 26, also fixed in the frame 21. This ledger bar serves to back up and support the web at the point where the right-hand fold is formed.

To hold the web securely during the folding operation and to provide a straight edge against which the web is folded, there is provided a gage plate 27 adapted to be brought down upon the web and clamped against the ledger bar 26 at a predetermined stage in the cycle of operations. The edge 28 of the plate 27 is so arranged as to be directly above the line of perforations 23 when in operative position. This situation is shown in Fig. 7, and exists at a point in the operation of the printing press when the feed mechanism is idle and the printing, punching and perforating units of the printing press are operating, at which time, of course, the paper does not travel.

As soon as the feed mechanism begins again to operate, the web starts to form a loop 29 (see Fig. 2) lying over the surface of the plate 27, as shown in dotted lines in Fig. 7. At this time, a creasing bar 30 is caused to move in the direction of web travel from a position shown in Fig. 7, where it is located beneath the plane of the table 25, ledger bar 26 and the web, upwardly and to the left as viewed and over the top of the plate 27, with a result that the web at the line of perforations, that is, at the point where the edge 28 of the plate 27 is located, is folded over and creased. This creasing action is very easily accomplished and does not require a great deal of pressure because of the weakened condition of the web by the line of perforations, and a slight urge in the folding direction will cause the web to be easily folded on the line of perforations.

So far as some of the aspects of the invention are concerned, this creasing bar is all that is needed to engage the web at the fold. However, since the operations of the machine are expedited by the withdrawal of the plate 27 as soon as possible to an out-of-the-way position, the creasing bar 30 is provided with clamping fingers 31 which, in operative position, engage the folded web directly above notches 32 in the gage plate 27 (see Fig. 9) to hold the web rigidly against the ledger bar 26, as shown in Fig. 2, independently of the folding plate 27. Immediately upon the conclusion of this operation, the plate 27 is withdrawn from between the fold 33 and moved to the position shown in Fig. 3.

In order to accomplish its movement above referred to, the plate 27 is mounted on arms 34 secured to discs 35, which in turn are fastened to a shaft 36 having bearings in the side plates 37 of the frame 21. One of these

discs 35 is provided with a pawl 38 adapted to engage a ratchet tooth 39 carried by a gear 40 rotatably mounted on the shaft 36 and confined against lateral motion between the disc 35 and the bearing in the side plate 37 of the frame. The gear 40 meshes with a rack 41 mounted on guides 42 in the frame and having at its lower end a link 43 connected to lever 44 secured on a shaft 45 pivoted in the side plates 37 of the frame. The end of the lever 44 opposite to that at which the link 43 is connected is provided with a roller 46 for engaging a cam bar 47 adapted to reciprocate in the direction of the travel of the web, that is longitudinally of the machine.

When the parts are in the position shown in Fig. 2, with the loop 29 partly formed and the gage plate 27 in operative position holding the web against the ledger bar 26, the roller 46 lies in a dwell 48 in the cam bar 47. The cam bar 47 is connected to the power shaft of the press in the manner hereinafter described, so that immediately after this condition exists, the cam bar moves to the right as viewed in Fig. 2, and causes the roller to be depressed and the rack 41 to be raised. The ratio between the movements of the rack 41 and gear 40 is such that the plate 27 is moved 180 degrees, that is to say to the position shown in Fig. 3. The rack is caused to descend and the roller rises when the latter is located under the dwell 48 in the cam bar 47 by means of a spring 49 connected to the lever 44 and anchored on the frame of the machine.

The movement of the creasing bar 30 to and from operative position is also controlled by the cam bar 47. For this purpose, the creasing bar 30 is carried by a pair of arms 50 secured to a shaft 51 and having a roller 52 located in the path of a cam 53 carried by the cam bar 47. When the cam 53 engages the roller 52, it rocks the arm 50 clockwise so as to withdraw the creasing bar 30 from its operative position shown in Fig. 2 to its inoperative position, where it is located below the plane of the path of the web as shown in Fig. 7. The creasing bar remains in this position until the roller 52 rides down the incline on the cam 53, at which time springs 54 connected to the arms 50 and anchored on the ledger bar cause the arms 50 to move counter-clockwise.

The creasing bar 30 is secured to an angle bar 55 pivotally mounted at 56 on the arms 50 and is urged to move downwardly by reason of the provision of springs 57 between the angle bar 55 and the arms 50. When the arms 50 are rocked clockwise, the creasing bar 30, after it leaves the fold 33 in the web, rides down an incline 58 on the ledger bar and remains in a substantially horizontal position below the path of the web. This is

an important feature of the present invention, for the creasing bar with its spring fingers 31 forms a continuation of the table 25 so as to prevent any draping of the web from the bight of the feed rollers 12 to the ledger bar. When the arms 50 are permitted so to do by the cam 53 at the proper time, the spring 54 pulls the creasing bar 30 in the direction of web travel with the result that it 10 rides up the incline 58 pushing the web upwardly and then creasing it over the gage plate to form the fold 33, yielding upwardly as permitted by the springs 57 in this operation.

15 The creasing bar 30 is provided with a rectangular opening 59 into which the clamping fingers 31 extend. These fingers are comparatively stiff and have a firm gripping action on the folded web. Due to the provision of the notches 32 in the gage plate 27, the fingers 31 actually bear down on the fold 33 before the gage plate 27 is withdrawn from the fold. The ends of the fingers 31 never extend below the creasing bar 30 and 20 hence do not engage the web until the latter has been folded by the creasing bar.

25 The manner of operating the cam bar 47 will be described below. Suffice it to say at this point that after the parts described above assume the position shown in Fig. 4, which is accomplished at the very beginning of the feeding operation of the rollers 12, they remain in these positions during the feeding of the form A which has been provided with the fold 33, and also during the feeding of the next adjacent form B.

30 After the feeding of the form B is concluded and while the printing and perforating units of the press are functioning, the fingers 31 and the creasing bar 30 are withdrawn to the position shown in Fig. 7 to permit the web to be released, so that the fold 33 may drop off the ledger bar and allow the end of the overlying form B to rest directly upon the ledger bar. Due to the accurate control of the web 22 by the feeding means, the line of perforations 23 between the forms B and C is in exactly the right position on the ledger bar, so that when the 35 folding plate 27 is swung down (which is done as soon as the creasing bar 30 and fingers 31 have been withdrawn), the edge 28 of the gage plate 27 will lie on the line of perforations 23. When the feeding operation is resumed, the form C starts to make a loop 29 and the creasing bar 30 again operates to make another right-hand fold 33 in the web, whereupon the fingers 31 hold the web in creased condition on the ledger bar.

40 When the right-hand fold 33 leaves the ledger bar 26, the folded web falls in a pile 60 on a supporting table 61 carried by the end 10 of the frame 11.

45 It has been found in practice that the right-hand folds 33 produced by the gage

plate 27 and the creasing bar 30 are sufficient to produce the zig-zag folded pile 60, for the left-hand fold 62 may be produced by the weight of the other forms which follow it and finally rest upon it. Even if the weight 70 of the forms were not sufficient to produce a sharp crease at the left-hand fold 62, this may be done from time to time by the operator pressing down the pile by hand.

75 However, to produce these left-hand folds 62 in the machine so that no hand-operation is needed and for other purposes, the present invention provides a carriage 63 adapted to ride in tracks 64 on the side plates 37 of the folding device frame 21 and having mounted thereon a pressing brush 65. At the beginning of the feeding operation, that is when the loop 29 is being formed, the brush 65 is located in position adjacent the ledger bar as shown in Fig. 3, and is also elevated above 80 the plane of the loop 29, while a table 66 which is mounted on the carriage 63 has its end located adjacent the ledger bar, so that the loop 29 may extend over onto the table 66, as shown in dotted lines in Fig. 3, during 85 the continuation of the feeding of the web.

90 The brush 65 extends transversely of the web 22 and is secured to a shaft 67 journaled in vertically extending arms 68 on the carriage 63. The shaft 67 also has secured to its levers 69 to each of which is connected a link 70 whose lower end is connected to an arm 71. Both arms 71 are secured to a shaft 72 mounted in arms 73 secured to the carriage 63. One of the arms 71 is in the form of a bell-crank and has another arm 74 to which the cam bar 47 is pivotally connected at 75. In the idle position of the cam bar 47, that is to say the position shown in Fig. 3, the arms 69 of the brush structure engage stop pins 76 mounted in the arms 68 in which position the brush 65 is elevated above the plane of the loop 29. The parts assume these positions until the loop 29 is completely formed as shown in 100 Fig. 4, that is to say when the feeding operation of form B has been concluded. Then, during the printing operations of the press, the cam bar 47 is moved to the left as viewed in Fig. 4. The first thing that occurs is that the cam bar 47, through the bell-crank 71-74, rocks the shaft 72 and causes the links 70 to be raised. This causes the brush 65 to be rotated so as to move downwardly against the form B until movement 105 of the brush is limited by the engagement of arms 77, integral with the arms 69, with the stop pins 76. Continued movement of the cam bar causes the brush and carriage to be moved toward the left to press down 110 the form B on the form A and slide along the surface of form B until the end of the loop is reached, during which operation the web is caused to crack along the line of perforations 23 and be sharply creased by the 115

120

125

130

downward pressure of the brush thereagainst.

In Fig. 5, the brush is shown in a position intermediate its limits of travel, while in Fig. 6 the brush is shown as having just passed over the fold 62.

At this point in the cycle of operations, the folded forms A and B at their ends adjacent their folds 62 may slip off the end 10 of the table 66 if the web is sufficiently flexible to permit this. However, whether it does so or not is immaterial, for upon further movement of the carriage, the end of the table is moved beyond the fold 62 and 15 the folded forms A and B are allowed to drop onto the pile 60 supported by the table 61. At the same time that this is being done, the fingers 31 and the creasing bar 30 are being withdrawn to permit release of 20 the fold 33 at the beginning of the form A, and in Fig. 7 both these operations are assumed to have been completed and the forms A and B are shown in the act of falling onto the pile 60. Before the feeding operation 25 is again resumed, the gage plate 27 is brought down into position on the ledger bar. This gage plate is so shaped as to have a slight wiping action on the web before it reaches its final position so as to 30 draw the web taut between the ledger bar and the feed rollers 12. The weight of the web depending from the ledger bar 26 should be sufficient to do this, but the wiping action is provided to insure this taut condition of the web so that the point of fold will be controlled solely by the feed mechanism.

In order that the functions of the various parts of the folding machine might be better understood, reference has been omitted 40 above to the means for operating the cam bar 47 which, it will be seen, controls the operation of the fold producing mechanism. Any suitable mechanism may be employed for coordinating the operation of the cam bar with that of the press. Efficient means for accomplishing this, however, is disclosed in Figs. 1, 11 and 12, in which the cam bar 47 is connected by a pin 78 to a link 79, which in turn is connected to an arm 80 secured to a shaft 81 to which is also secured an arm 82 connected by a link 83 to a lever 84 which carries between its ends a cam following roller 85. The roller 85 rides in a track 86 which is heart-shaped in a cam-disk 50 55 58 62 67 72 76 81 85 89 93 97 101 105 110 114 118 122 126 130 134 138 142 146 150 154 158 162 166 170 174 178 182 186 190 track 86 and starts the retracting movement of the cam bar 47. However, before the carriage can move back with the cam bar, the brush is rocked upwardly out of the way by its link connection 70 until the arms 69 engage the pins 78, as shown in Fig. 2, because the resistance offered by the rotation of the brush is less than that offered by the carriage.

10 During this initial retracting movement of the cam bar, the roller 52 rides down the incline 93 on the cam 53 and permits the spring 54 to move the creaser bar 30 to the position shown in Fig. 3 to form the fold 33. At the same time or rather shortly before this occurs, the roller 46 moves into the dwell 48 in the cam bar so as to move the rack 41 downwardly and get it in position to operate. After the fingers 31 have gripped the fold 33, the roller 46 is forced out of the dwell 48 causing the rack to move upwardly and rotate the gage plate 27 one half a revolution, that is to say to the position shown in Fig. 3, where it too is out of the way of the advancing loop 29. The continued movement of the cam bar 47 causes the carriage to be moved to the position shown in Fig. 3, in which it remains until the form being fed and the one following it is in position for the formation of the left-hand fold 62.

15 The gage plate 27 may be held in its operative and inoperative positions by any suitable means. In the accompanying drawings, this means comprises a detent pawl 94 pivoted at 95 and normally under pressure of the spring 96 which urges it into notches 97 in the disk 35 secured to the shaft 36 and carrying the folding bar 27.

20 The length of movement of the brush 65 and the table 66 is made sufficient to function with a form of maximum length capable of being printed in the press, and since the left-hand fold 62 is formed by the wiping or sweeping action of the brush 65, no adjustment or change in the mechanism need be made when the forms are less length, nor is it necessary to adjust the position of the ledger bar 26 and gage plate 27 when the device is used in presses of the type which permit adjustment of the printing instrumentalities, in which case the line of perforations 23 may be made to always come to rest in the same position irrespective of the length of the forms being printed.

25 When, however, the printing press is not of this type, but has a stationary (not adjustable) printing head, the line of perforations 23 may come to rest when forms of different lengths are printed at various points within a zone equal to half the length of the maximum length forms. Yet, they will, of course, always repeatedly come to rest at the same place during the printing of a particular job.

Accordingly, to permit the edge 28 of the gage plate 27 to be adjusted to exactly that position at which the line of perforations 23 happens to come to rest in each particular job, the folding device frame 21 is adjustably mounted on the printing press frame 11. For this purpose, the entire folding device frame 21 is adjustably mounted and has hangers 98 adapted to ride upon the upper edge 99 of the printing press frame 10, see Figs. 1 and 12. When adjusted to the proper position, the folding frame 21 may be locked against accidental movement by bolts 100 sliding in slots 101 in the frame 10 and carried by the folding frame 21.

30 In order to facilitate the adjusting movement of the folding frame 21, the latter is provided with an adjusting shaft 102 carrying gears 103 meshing width racks 104, one located at each side of the machine. This shaft has a square head 105 to receive a socket wrench or key by means of which the frame 21 may be moved longitudinally of the frame 10. To further steady and support the folding frame 21 on the printing press frame 10, screws 106 are provided in the hangers 98 so as to clamp against the rack 104.

35 During this adjustment, the driving gear 91 moves with the folding machine frame, for it is confined between the bevel gear 90 and a stop collar 107 carried by the frame 21. Yet, it is always connected to rotate with the power shaft 19 because a spline 108, which it carries, rides in the longitudinal groove 109 in the shaft.

40 Thus it will be seen that in setting up a job, the only attention that needs to be paid to the folding device is to see that edge 28 of the gage plate 27 lies directly upon the line of perforations 23, which is accomplished by the longitudinal adjustment of the frame 21.

45 In order that the gap which must be provided between the ledger bar 26 and the feed rollers 12 to permit adjustment of the folding device may be kept closed in all positions of the latter, the table 25 is made in two parts 25a and 25b telescoping with each other, the part 25a being carried by and secured to the frame 21, while the part 25b is secured to the frame 12a carrying the feed rolls 12.

50 It will be remembered that the folding device operates during only one half of the rotation of the cam disk 87, and consequently only once during two revolutions of the power shaft. In order that the folding device may start to operate during either revolution of the shaft, the pin or bolt 89 is movable so that it can be withdrawn from the hole 89a in the disk 87, whereupon the disk 87 may be rotated by hand one-half revolution to align the pin 89 with another hole 89b diametrically opposite the

first mentioned hole 89b in the cam disk 87 while the gears 90 and 91 are not rotating.

Variations and modifications may be made within the scope of this invention and portions of the improvements may be used without others.

Having thus described the invention, what is claimed as new and for which it is desired to obtain Letters Patent, is:—

1. A machine for folding a strip of fabric of indefinite length to form a zig-zag folded pile comprising a gage plate held stationary in a predetermined position during the folding operation; and web-advancing means operative to cause the web intermittently to stop with a line of fold thereon located in the said predetermined position.

2. A machine for folding a strip of fabric of indefinite length to form a zig-zag folded pile comprising means for intermittently advancing the web form-length intervals; and a gage plate held stationary during the folding operation and adapted to lie upon the web at the place thereof where the fold is to occur.

3. A machine for folding a strip of fabric of indefinite length to form a ziz-zag folded pile comprising web-advancing means to intermittently operate to feed the web form-length intervals and adapted to maintain control of the web between feeding operations, said web-advancing means comprises a variable throw device whereby the extent of advancement may be varied to feed webs having forms of different lengths; a gage plate along which the web is folded; and means for adjusting the normal operative position of the gage plate to permit the latter to be located at that point in the path of the web where the junction of two adjacent forms lies at the end of the feeding operation.

4. An all size folding machine having associated therewith variable-throw web-advancing means; and means in the path of the web and acting on the web while under the control of said web-advancing means for folding the web to produce a zig-zag folded pile, said means having a fixed throw of sufficient length to fold the web irrespective of the length of throw of the web-advancing means.

5. An all size folding machine having associated therewith variable-throw web-advancing means; and means in the path of the web and acting on the web while under the control of said web-advancing means for folding the web to produce a zig-zag folded pile, said means having a fixed throw of sufficient length to fold the web irrespective of the length of throw of the web-advancing means, the positions of both right-hand and left-hand folds in the web being

controlled solely by the web-advancing means.

6. A folding machine for use with printing presses having associated therewith web-advancing and controlling means and comprising means for folding a web of indefinite length printed by said printing press so as to form a zig-zag folded pile; and operating connections between the said press and said folding means adapted to produce one cycle of operations of the folding means for each two cycles of operations of the press.

7. A folding machine for producing from a continuous web a zig-zag folded pile comprising a ledger bar, located in the path of the web and over which the web is adapted to travel; a gage plate adapted to cooperate with the ledger bar to hold the web in predetermined position thereon and to determine the line of fold; and web-advancing means for moving the web so that the line of fold lies at the edge of the gage plate.

8. A folding machine for producing from a continuous web a zig-zag folded pile comprising a ledger bar, located in the path of the web and over which the web is adapted to travel; a gage plate adapted to cooperate with the ledger bar to hold the web in predetermined position thereon and to determine the line of fold; web-advancing means for moving the web so that the line of fold lies at the edge of the gage plate; and a creaser bar adapted to fold said web over said gage plate to produce a fold in the web.

9. A folding machine for producing from a continuous web a zig-zag folded pile comprising a ledger bar, located in the path of the web and over which the web is adapted to travel; a gage plate adapted to cooperate with the ledger bar to hold the web in predetermined position thereon and to determine the line of fold; web-advancing means for moving the web so that the line of fold lies at the edge of the gage plate; a creaser bar adapted to fold said web over said gage plate to produce a fold in the web; and spring fingers for engaging the web at the fold thus formed by the creaser bar to hold the web against the ledger bar independently of said gage plate.

10. A folding machine for producing from a continuous web a zig-zag folded pile comprising a ledger bar, located in the path of the web and over which the web is adapted to travel; a gage plate adapted to cooperate with the ledger bar to hold the web in predetermined position thereon and to determine the line of fold; web-advancing means for moving the web so that the line of fold lies at the edge of the gage plate; a creaser bar adapted to fold said web over said gage plate to produce a fold in the web; spring fingers for engaging the web at the fold thus formed by the creaser bar to hold the web

against the ledger bar independently of said gage plate; and means for withdrawing the gage plate from between the fold produced by the creaser bar whereby the fold is held to the ledger bar solely by the spring fingers.

11. A folding machine for producing from a continuous web a zig-zag folded pile comprising a ledger bar, located in the path of the web and over which the web is adapted to travel; a gage plate adapted to cooperate with the ledger bar to hold the web in pre-determined position thereon and to determine the line of fold; web-advancing means for moving the web so that the line of fold lies at the edge of the gage plate; a creaser bar adapted to fold said web over said gage plate to produce a fold in the web; spring fingers for engaging the web at the fold thus formed by the creaser bar to hold the web against the ledger bar independently of said gage plate; means for withdrawing the gage plate from between the fold produced by the creaser bar whereby the fold is held to the ledger bar solely by the spring fingers; and a table upon which the web is supported as the web continues to advance after the fold has been produced by the creaser bar to support the loop just formed in substantially horizontal position.

12. A folding machine for producing from a continuous web a zig-zag folded pile comprising a ledger bar, located in the path of the web and over which the web is adapted to travel; a gage plate adapted to cooperate with the ledger bar to hold the web in pre-determined position thereon and to determine the line of fold; web-advancing means for moving the web so that the line of fold lies at the edge of the gage plate; a creaser bar adapted to fold said web over said gage plate to produce a fold in the web; and a table upon which the web is supported as the web continues to advance after the fold has been produced by the creaser bar to support the loop just formed in substantially horizontal position.

13. A folding machine for producing from a continuous web a zig-zag folded pile comprising a ledger bar, located in the path of the web and over which the web is adapted to travel; a gage plate adapted to cooperate with the ledger bar to hold the web in pre-determined position thereon and to determine the line of fold; web-advancing means for moving the web so that the line of fold lies at the edge of the gage plate; a creaser bar adapted to fold said web over said gage plate to produce a fold in the web; spring fingers for engaging the web at the fold thus formed by the creaser bar to hold the web against the ledger bar independently of said gage plate; means for withdrawing the gage plate from between the fold produced by the creaser bar whereby the fold is held to the ledger bar solely by the spring

fingers; a table upon which the web is supported as the web continues to advance after the fold has been produced by the creaser bar to support the loop just formed in substantially horizontal position; and means adapted to engage the loop supported by the table to produce in the web a fold opposite in direction to that produced by the creaser bar.

14. A folding machine for producing from a continuous web a zig-zag folded pile comprising a ledger bar, located in the path of the web and over which the web is adapted to travel; a gage plate adapted to cooperate with the ledger bar to hold the web in pre-determined position thereon and to determine the line of fold; web-advancing means for moving the web so that the line of fold lies at the edge of the gage plate; a creaser bar adapted to fold said web over said gage plate to produce a fold in the web; and means adapted to engage the loop resulting from further advance of the web after the formation of the fold to produce in the web a fold opposite in direction to that produced by the creaser bar.

15. A folding machine for producing from a continuous web a zig-zag folded pile comprising a ledger bar, located in the path of the web and over which the web is adapted to travel; a gage plate adapted to cooperate with the ledger bar to hold the web in pre-determined position thereon and to determine the line of fold; web-advancing means for moving the web so that the line of fold lies at the edge of the gage plate; a creaser bar adapted to fold said web over said gage plate to produce a fold in the web; means adapted to engage the loop supported by a table provided in its path of produce in the web a fold opposite in direction to that produced by the creaser bar; and means for withdrawing the table from under the web to permit the folded web to fall in a pile.

16. A folding machine for producing from a continuous web a zig-zag folded pile comprising a ledger bar, located in the path of the web and over which the web is adapted to travel; a gage plate adapted to cooperate with the ledger bar to hold the web in pre-determined position thereon and to determine the line of fold; web-advancing means for moving the web so that the line of fold lies at the edge of the gage plate; a creaser bar adapted to fold said web over said gage plate to produce a fold in the web; spring fingers for engaging the web at the fold thus formed by the creaser bar to hold the web against the ledger bar independently of said gage plate; and means for retracting the spring fingers to release the folded portion of the web supported by the ledger bar and permit the same to fall from the ledger bar so that the overlying unfolded portion of the web may rest directly thereon.

17. A folding machine for producing from a continuous web a zig-zag folded pile comprising a ledger bar, located in the path of the web and over which the web is adapted to travel; a gage plate adapted to cooperate with the ledger bar to hold the web in predetermined position thereon and to determine the line of fold; web-advancing means for moving the web so that the line of fold 5 lies at the edge of the gage plate; a creaser bar adapted to fold said web over said gage plate to produce a fold in the web; spring fingers for engaging the web at the fold thus formed by the creaser bar to hold the 10 web against the ledger bar independently of said gage plate; means for withdrawing the gage plate from between the fold produced by the creaser bar whereby the fold is held to the ledger bar solely by the spring fingers; a table upon which the web is supported as the web continues to advance after the fold has been produced 15 by the creaser bar to support the loop just formed in substantially horizontal position; means adapted to engage the loop supported by the table to produce in the web a fold opposite in direction to that produced by the creaser bar; and means for retracting the spring fingers to release the folded portion of the 20 web supported by the ledger bar and permit the same to fall from the ledger bar so that the overlying unfolded portion of the web may rest directly thereon. 25
18. A folding machine for producing from a continuous web a zig-zag folded pile comprising a ledger bar, located in the path of the web and over which the web is adapted to travel; a gage plate adapted to cooperate with the ledger bar to hold the web in predetermined position thereon and to determine the line of fold; web-advancing means for moving the web so that the line of fold lies at the edge of the gage plate; a creaser bar adapted to fold said web over 30 said gage plate to produce a fold in the web; spring fingers for engaging the web at the fold thus formed by the creaser bar to hold the web against the ledger bar independently of said gage plate; means for retracting the spring fingers to release the folded portion of the web supported by the ledger bar and permit the same to fall from the ledger bar so that the overlying unfolded portion of the web may rest directly thereon; and means for moving the gage plate into position to hold the portion of the web next to be folded against the ledger bar. 35
19. A folding machine for producing from a continuous web a zig-zag folded pile comprising a ledger bar, located in the path of the web and over which the web is adapted to travel; a gage plate adapted to cooperate with the ledger bar to hold the web in predetermined position thereon and to determine the line of fold; web-advanc- 40
- ing means for moving the web so that the line of fold lies at the edge of the gage plate; a creaser bar adapted to fold said web over said gage plate to produce a fold in the web; spring fingers for engaging the web at the fold thus formed by the creaser bar to hold the web against the ledger bar independently of said gage plate; means for withdrawing the gage plate from between the fold produced by the creaser bar whereby the fold is held to the ledger bar solely by the spring fingers; a table upon which the web is supported as the web continues to advance after the fold has been produced by the creaser bar to support the loop just 45 formed in substantially horizontal position; means adapted to engage the loop supported by the table to produce in the web a fold opposite in direction to that produced by the creaser bar; and means for moving the table in coordination with the movement of the loop-engaging means so that after the latter has caused the web to be creased the table moves from under the creased portion of the web to permit its escape and allow it to fall on the pile. 50
20. A folding machine for producing from a continuous web a zig-zag folded pile comprising means for intermittently advancing the web form lengths, and separate means for folding the web. 55
21. A folding machine for producing from a continuous web a zig-zag folded pile comprising a creaser bar for producing the folds which extend in one direction; and a wiping device for producing the folds which extend in the other direction. 60
22. A folding machine for producing from a continuous web a zig-zag folded pile comprising means for advancing the web form lengths; a wiping device for producing the folds which extend in one direction; and a creaser located between the wiping device and the feeding means for producing the folds extending in the other direction. 65
23. A folding machine for producing from a continuous web a zig-zag folded pile comprising intermittently operating means for feeding the web form lengths; separate means for producing the right-hand and left-hand folds in the web; and means for operating said separate means one after the other, each once for each two operations of the feeding means. 70
24. A folding machine for producing from a continuous web a zig-zag folded pile comprising a straight edge along which the web is folded; and means for withdrawing the straight edge from the fold and moving it to position preparatory to re-engaging a succeeding portion of the web at a subsequent point in the operation of the machine. 75
25. A machine for folding a strip of fabric of indefinite length to form a zig-zag folded pile comprising means for intermit- 80

tently advancing the strip predetermined lengths; means for producing folds of one hand while the strip is advancing; and separate means for producing folds of the other hand during a period of intermission between advancing movements of the strip.

26. A folding machine for producing from a continuous web a zig-zag folded pile comprising a ledger bar, located in the path 10 of the web and over which the web is adapted to travel; a gage plate adapted to cooperate with the ledger bar to hold the web in predetermined position thereon and to determine the line of fold; web-advancing 15 means for moving the web so that the line of fold lies at the edge of the gage plate; means adapted to fold said web over said gage plate to produce a fold in the web, said means including spring fingers for engaging 20 the web at the fold thus formed to hold the web against the ledger bar independently of said gage plate.

27. A folding machine for producing from a continuous web a zig-zag folded pile 25 comprising a ledger bar, located in the path of the web and over which the web is adapted to travel; a gage plate adapted to cooperate with the ledger bar to hold the web in predetermined position thereon and to de- 30 termine the line of fold; web-advancing means for moving the web so that the line of fold lies at the edge of the gage plate; means adapted to fold said web over said gage plate to produce a fold in the web, said 35 means including spring fingers for engaging the web at the fold thus formed to hold the web against the ledger bar independently of said gage plate; and means for withdrawing the gage plate from between the fold pro- 40 duced by the said means whereby the fold is held to the ledger bar solely by the spring fingers.

28. A folding machine for producing from a continuous web a zig-zag folded pile 45 comprising a ledger bar, located in the path of the web and over which the web is adapted to travel; a gage plate adapted to cooperate with the ledger bar to hold the web in predetermined position thereon and to de- 50 termine the line of fold; web-advancing means for moving the web so that the line of fold lies at the edge of the gage plate; means adapted to fold said web over said 55 gage plate to produce a fold in the web, said means including spring fingers for engaging the web at the fold thus formed to hold the web against the ledger bar independently of said gage plate; means for withdrawing the 60 gage plate from between the fold produced by the said means whereby the fold is held to the ledger bar solely by the spring fingers; and a table upon which the web is supported as the web continues to advance 65 after the fold has been produced by the said

means to support the loop just formed in substantially horizontal position.

Signed at Hoboken, in the county of Hudson, and State of New Jersey, this 21st day of October, 1928.
